UNITED STATES PATENT OFFICE.

ELMER E. PATTEN, OF ST. LOUIS, MISSOURI ASSIGNOR TO ST. LOUIS CASH REGISTER COMPANY, OF ST. LOUIS, MISSOURI, A CORPORATION OF MISSOURI.

CASH-REGISTER.

1,079,360.

Specification of Letters Patent.

Patented Nov. 25, 1913.

Application filed September 2, 1911. Serial No. 647,321.

To all whom it may concern:

Be it known that I, ELMER E. PATTEN, a citizen of the United States, residing at the city of St. Louis, State of Missouri, have invented a certain new and useful Improvement in Cash-Registers, of which the following is a full, clear, and exact description, such as will enable others skilled in the art to which it appertains to make and use the same, reference being had to the accompanying drawings, forming part of this specification, in which—

Figure 1 is a top plan view of my improved cash register with the casing removed. Fig. 1^a is a detailed view of the segment which operates the type wheel. Fig. 2 is a front elevational view of the same. Fig. 3 is a rear elevational view of the same. Fig. 4 is a side elevational view of the same. Fig. 5 is a detailed view illustrating the casing. Fig. 6 is a detailed view illustrating a part of the paper feeding mechanism. Fig. 7 is a vertical longitudinal sectional view through the machine. Fig. 8 is a side elevational view of the totalizers, as seen from the left-hand side of the machine. Fig. 8^a is a similar view showing the parts in changed position. Fig. 9 is an enlarged front elevational view of the totalizers. Fig. 10 is a detailed view of the hundreds, tens and unit wheels respectively. Fig. 11 is a detailed side elevational view of the totalizers and their carrying mechanism. Fig. 12 is a detailed view of the actuating pawl for the "No sale" register or totalizer. Fig. 13 is a detailed view of the actuating pawl for the tens and hundreds of dollars wheels. Fig. 14 is a detailed view of the tens and hundreds of dollars wheels respectively. Fig. 15 is a detailed view of one of the indicating wheels. Fig. 16 is a detailed view of the disk carrying a trip projection for the carrying mechanism which is attached to the indicating wheel. Fig. 17 is a detailed view illustrating the restraining pawls for the totalizers. Fig. 18 is a front elevational view of the cylinder indicating mechanism. Fig. 19 is a side elevational view of said mechanism showing the dollars segment. Fig. 19^a is a similar view showing the cents segment. Fig. 20 is a detailed view of the means for operating the "No sale" indicator. Fig. 21 is a detailed view of the means for operating the dollar indicating cylinder. Fig.

22 is a detailed view of the tens controlling lever. Fig. 23 is a detailed view of the units controlling lever. Fig. 24 is a detailed view of the rocker frame. Fig. 25 is a detailed view of the carrying mechanism showing the parts in carrying position. Fig. 26 is a side elevational view of the composition key and its connections. Fig. 27 is a modified form of operating handle showing means for deferring the return of the register operating segments. Fig. 28 is a side elevational view of the clerk designating mechanism. Fig. 29 is a plan view of the structure shown in Fig. 28. Fig. 30 illustrates a portion of the record strip.

This invention relates to a new and useful improvement in cash registers, the object being to construct a machine of the character described in such manner that there are comparatively few parts and therefore the machine may be cheaply manufactured.

One feature of my improved machine is the utilization of a single lever which is universally mounted so as to swing horizontally opposite the number to be registered, and then move vertically to register, indicate and record said number.

Another feature resides in the peculiar construction of the controlling plates which coöperate with the handle whereby one or more of said controlling plates are operated to effect such registration.

Another feature of the invention resides in the employment of a composition key whereby a large number composed of one or more smaller numbers may be registered and recorded, as separate numbers, but indicated as a single number.

Another feature is the provision of means whereby when the composition key is depressed, the drawer cannot be opened until all of the component parts of the number have been registered, indicated and recorded.

Separate counting mechanisms are provided to register the numbers indicating different amounts of sales and the number of times that the handle is operated to open the drawer when "no sale" is made.

My invention consists also in the construction, arrangement and combination of the several parts, all of which will be herein-after pointed out in the claims.

In the drawings: 1 indicates the side frames of the machine which are connected

together by suitable cross bars, and in which the shafts or pivot rods are mounted. Between these side frames is arranged a drawer 2 which, when released, is moved outwardly by a spring 3. Arranged at the front of the machine and between the side frames 2 is a spacing plate 4 in the form of an inverted comb whose teeth are beveled at their upper ends to provide guiding mouths to the several slots. A plate 5 is arranged in juxtaposition to plate 4 (see Figs. 2 and 5) upon which are placed indicating numbers which determine the position of the operating handle. The operating handle is indicated at 6 and is provided with an upwardly opening slot, see Fig. 4, at its upper end to embrace the outwardly extending flange of plate 5, the button or head of said operating handle being provided with an indicating point designed to be placed opposite the amount to be registered. The operating handle is pivoted at 7 by means of a horizontally disposed pivot pin to a swinging plate 8, which plate is provided with vertical pivot points co-operating with the cross bars 9 and 10. The rear end of the operating handle 6 carries a spring-held tappet 11 which co-operates with a notched plate 12, carried by the rear end of the plate 8, so as to compel a full stroke of the operating handle in a manner well known. In order to prevent the operating handle from being operated when moved too suddenly, or when being struck a blow, as for instance by the falling of a package thereon, I pivotally mount a restraining plate 13 upon the plate 8 which plate has a recess for co-operating with a pin 14 on the operating handle. When the operating handle is properly operated, the pin 14 rides up the inclined upper edge of the slot permitting the plate 13 to swing on its pivot until said plate 13 strikes a pin 15 on plate 8. The rear end of plate 13 is bent under the operating handle, so that as the operating handle is restored to normal position, the plate 13 is moved in proper relation to the pin 14. When the operating handle is moved too suddenly, as when struck a blow, the plate 13 will prevent the operating handle from being operated as the relation of the pin 14 to the upper edge of the recess is such that the operating handle is locked in position when too great a downward pressure is exerted on its forward end. 16 indicates a rocker plate concentric with respect to the pivotal axis of movement of the plate 8 and pivotally mounted upon castings which connect the cross bars 9 and 10, the pivotal point of this rocker frame being co-incident with that of the operating handle. The rear ends of this rocker frame are provided with weights 17 which I prefer to use in place of springs because they exert a constant energy upon the rocker frame to restore the same, where-

as springs would exert a variable pressure upon said frame.

The rocker frame may of course have springs connected to it either to assist the weights in their action, or to constitute the sole restoring medium for said rocker frame.

The operating handle is provided with an L-shaped extension 6^a (see Fig. 7) which extends under the rocker frame so that when the operating handle is depressed, the rocker frame is moved with it and when said handle is raised, the rocker frame will also be positively restored to position, although in practice the operating handle is depressed and then released, the weights or springs connected to the rocker frame restoring the operating handle. One member of the rocker frame is extended rearwardly as indicated at 16^a where it is provided with a tappet 17^a carrying a roller on its end which co-operates with a beveled lower edge of a lever 18 pivoted to the adjacent side frame so as to rock said lever on the upward movement of the member 16^a. Lever 18 is provided with a shoulder 18^a so that when the roller on the tappet rocks said lever and comes to a position opposite the shoulder, it will permit the lever 18 to remain in its normal position on the down stroke of the member 16^a. The purpose of this rocking lever 18 is to release the indicating cylinders to zero so that they may be reset to indicate a number being registered in the machine, as will hereinafter more fully appear. In addition to releasing the indicating cylinders, the rocker frame 16 also operates the paper feeding mechanism and the carrying mechanism of the totalizers, as will hereinafter appear.

I will now describe the means for introducing numbers into the registering mechanism and will first direct attention to Fig. 2 wherein it will be seen that the plate 5 at the left bears the characters "01" to "04" inclusive, indicating cents, so that when the pointer on the operating handle is placed opposite any of these numbers, the registering mechanism will be correspondingly operated to accumulate the proper number and the indicating cylinder is moved to indicate such number. The letters "N. S." on plate 5 mean "no sale" and when the operating handle is placed opposite this point and depressed, the registering mechanism for indicating the number of times the drawer is opened, will be operated and the indicating cylinders returned to zero. The figures "05—10—15, etc" indicate cents progressively in multiples of 5 up to 95, and when the handle is positioned opposite any of these numbers and depressed, the corresponding number will be registered in the registering mechanism. At the right of plate 5 appears the character "\$1" and when the operating handle is positioned at this

point and depressed, the proper registering wheel will be operated and the indicating cylinder moved to indicate the registration of one dollar.

- 5 Referring now to Fig. 23, 19 indicates the units plate which is fixed to a shaft 20, said plate being connected by a sleeve on said shaft to a segment 21 which segment is adapted to be rocked forward when plate 19 is raised by the operating handle. When the operating handle is moved to indicate the units, cents, the rear end of said handle is located under one of the steps marked 1, 2, 3 and 4 so distanced from the rear end of the operating handle that when the handle engages one of said steps, the units plate will be raised so as to rock the segment 21 the distance of 1, 2, 3, or 4 teeth. Assuming that the handle is positioned to open the drawer without registering the number (no sale) the rear end of the operating handle will be located opposite a notch 19^a in the units plate and hence said plate will not be raised upon the operation of the handle.
- 25 19^b indicate projections or shoulders on the lower edge of the units plate, each of which, when engaged by the operating handle and raised, will move the segment 21 the distance of five teeth. Thus in the registration 30 of progressively higher numbers in multiples of five, each number containing five units will, when registered, cause the units plate to be lifted a distance to register five units in the totalizer wheel; and each number containing no units, will, when registered by operating the handle, permit the units plate to remain stationary as the operating handle will in the registration of such numbers, be located opposite one of the 35 recesses 19^a.
- In Fig. 22 I have shown the tens controlling plate 22 which is pivotally mounted upon the shaft 20. This tens plate is provided with a series of shoulders on its top 40 and bottom edges, that at the extreme right in Fig. 22 indicated at 22^a being so positioned with respect to the rear end of the operating handle that when said handle is operated, the tens plate will remain stationary.
- 45 This edge 22^a coincides with the arc of movement of the operating handle from and including .05 to the right of "No sale" to and including ".01". The next step 22^b will, when the operating handle engages the plate 50 to lift it at this point, cause the tens plate to be raised so that it and its conjoined segment 23 will move forward a distance of one space thus registering "1" in the tens registering wheel. These steps progressively increase the extent of movement of the tens plate, until the lowermost step is reached which, when the operating handle cooperates therewith, will cause the segment 23 to be rocked forward a distance of nine spaces.
- 60 65 24 indicates an arm pivotally mounted on

shaft 20 and whose rear end is bent as shown in Fig. 21 so that when the operating handle is moved to the extreme right by the operator its rear end will be positioned under the bent end 24 so as to raise said plate a distance of one tooth to register one dollar in the proper registering wheel. In doing this the operating handle of course does not operate either the tens or the units plates. Plate 24 has a segment 25 connected thereto for coöperating with the units dollar pinion of the totalizer.

The totalizer wheels are mounted upon a grooved shaft 26 having suitable bearings in side frame plates 27 pivotally mounted at 28 to bracket extensions on the cross bar 9. This frame is rocked rearwardly at the initial depressing movement of the handle by means of a rocking frame 29 (see Fig. 8) having a notch in its periphery which notch coöperates with a roller on an end of a tappet 30. The tappet 30 is carried by an arm 31 pivotally mounted to the side framing 2 and having a lateral projection 31^a on its end which extends over a rearward extension on one of the frames 27. The frame 29 is rocked by means of a link 32 connected to the rocker bar 16. When the handle is depressed, the roller on the end of the tappet 30 drops into the notch of the frame 29, and spring 33 rocks the arm 31 and holds the totalizer frame rearwardly until the frame 29 passes under the tappet 30 and permits said tappet to rise to its normal position. In rising the tappet 30 which is provided with a lateral projection 30^a engaging the arm 31 will, by the cam face 29^a on the rocking frame, lift the frame 31 and restore the totalizer frame to normal position. In this manner the totalizer wheels are thrown into mesh with the segmental racks 21, 23 and 25 at the commencement of the downward movement of the operating handle and held in mesh therewith until said handle starts to rise with the cam face 29^b and will lift the totalizer wheels out of engagement with their racks and prevent retrograde rotation thereof.

The counter for indicating the number of times that the drawer is opened and "no sale" made is shown in Figs. 10 and 11 and consists of the indicating wheels 34 bearing numbers from 1 to 9 inclusive and zero on their peripheries to which wheels are conjoined ratchet wheels 39 shown in Fig. 10. The wheel at the right in Fig. 10 is the units wheel and has a deep notch 39^a while the tens wheel shown at the center in Fig. 10 has a shallower notch 39^b. An operating pawl 40 is carried by an arm 41 pivotally mounted on a shaft 42 and normally held against the units wheel by means of a spring 43. Thus, whenever the arm 41 is vibrated, the pawl 40 is lifted and its tine 40^a will operate the units wheel until it drops into

the deep notch 39^a when the second tine 40^b will engage the tens wheel and move the tens wheel a distance of one tooth. When the tine 40^a operates in the ordinary way with its ratchet teeth, tine 40^b which drives the tens wheel and the tine 40^c which operates the hundreds wheel will be held out of engagement with said wheels respectively. When the deep notch in the units wheel ratchet is reached then the tine 40^b may operate the tens wheel the distance of one tooth or, if the tine 40^b drops into shallow notch 39^b, then the tine 40^c will be brought into engagement with the hundreds wheel and operate the latter the distance of one tooth simultaneously with the operation of the tens and units wheels.

The means for operating the timed driving pawl for the above described counting mechanism comprises a bail-like frame 44 pivotally mounted on shaft 20 and having a rearward extension 44^a, see Figs. 1 and 20 which rearward extension is provided with a bent rear end designed to be engaged by the operating lever when the same is positioned at "No sale". Bail 44 engages a cam face on the rear end of lever 41, see Fig. 7, so as to vibrate said lever every time the handle is operated when positioned at "No sale".

36 The totalizing wheels which are operated to accumulate the various registrations are indicated at 45, see Fig. 9, the indicating wheel at the extreme right of the series registering cents, the adjacent wheel of higher order dimes, and next dollars, tens of dollars, and so on. Each of these indicating wheels 45 has conjoined to it a ratchet wheel 46 and a disk 47 carrying a tripping projection on its periphery, see Fig. 16 for co-40 operating with the carrying mechanism.

The cents, dimes and dollars wheel are operated respectively by the segments 21, 23 and 25 as before described, and irrespective of whether or not said wheels are independently or simultaneously operated, the carrying mechanism about to be described is operative to carry from lower to higher orders.

Referring now to Fig. 11 wherein a segment 21 is shown out of mesh with its co-operating pinion, it will be observed that when the frame 27 is rocked rearwardly, it will engage pinion 46^a conjoined to the ratchet wheel 46 with a segment and rotate said pinion, its conjoined ratchet wheel and indicating wheel on the forward stroke of the segment. 48 indicates a restraining pawl pivotally mounted on a rod 49 having a bearing in the side frames 27, and which pawl 48 prevents backward rotation of the ratchet 46. Assuming for purposes of description that the disk 47 with its tripping projection shown in Fig. 11, is identified with the cents wheel and that the pinion 60 ratchet wheel and indicating wheel illus-

trated in said figure are identified with the dimes column, it will be seen that as the tripping projection rotates, it will engage a finger or shoulder 50^a on a tripping pawl 50 pivotally mounted on the rod 49. This pawl is held in operative position by a spring 51. A shoulder is provided at its forward end which shoulder normally restrains a driving pawl 52 from engaging the ratchet wheel of higher order. This driving pawl as shown in Fig. 9 is provided with a lateral extension 75 for co-operating with the tripping pawl 50.

In the normal operation of the machine when no carrying is effected, the carrying pawl 52 is vibrated idly by means of the following mechanism: On the shaft 42 are arms 53 upon whose forward ends are pivotally mounted carrying pawls 52. Arms 53 are provided with downward extensions to which are pivoted tappets 54 having rollers on their lower ends and provided with lateral projections on their upper ends for engaging the forward edge of the arm 53. A spring 55 tends to hold these tappets in normal position. A spring 56 holds the carrying pawls 52 in engagement with the tripping pawls 50 and the spring 51 also tends to maintain the engagement between the tripping pawls and carrying pawls. The rocking frame 29 before referred to carries cam projections 57 at its upper end which co-operate respectively with the rollers of the tappets 54 of the different carrying pawls, and in order to successively carry from lower to higher orders, these cam projections 57 are preferably arranged in a spiral series, as shown.

As the operating handle is depressed and the segment 21 is rocked forwardly to introduce the proper number into the register wheel, the tripping projection will depress the forward end of the tripping pawl 50 and permit the carrying pawl 52 to be moved, under the action of its spring 56, into engagement with the ratchet identified with the next adjacent register wheel of higher order. At the same time, frame 29 moves rearwardly and the cam projections 57 are successively moved under and behind the tappets 54, said tappets idly vibrating to permit this. Upon the initial upward movement of the operating handle, the segments are disengaged from the registering pinions and as the frame 29 rocks forwardly, the tappets 54 are successively engaged, and any carrying pawl 52 which has been released and which is in engagement with the ratchet wheel of next higher order, will be lifted and rotate its engaged ratchet wheel the distance of one tooth. All of the carrying pawls are of course thus lifted, but only those ratchet wheels of higher order will be operated by the carrying pawls which have been tripped. The other carrying pawls 52 while lifted cannot operate their ratchet 130

wheels because they are held out of engagement therefrom by the non-tripped tripping pawls. In order to absorb high numbers carried from actuated register wheels, 5 I may add one or two additional wheels, as for instance tens of dollars and hundreds of dollars as shown at the left in Fig. 9. These wheels have no pinions conjoined to them, and as they can only receive motion from a 10 wheel of lower order and are never operated more than one step at a time, I provide the same with recesses of varying depths and effect carrying from one to the other by means of a carrying pawl 58 which operates 15 similar to the fine carrying pawl 40 before described with respect to the counting indicator 34.

To restore the registering mechanism to zero position, I provide the end of shaft 26 20 with a hand wheel 60, see Figs. 1 and 2 and mount in each of the indicating wheels 34 and 45, a spring-pressed pawl 61, see Fig. 15, which pawls are designed to fall into a longitudinal groove in the shaft 26 and rotate the disks in the same direction as when 25 said disks are being driven by their segments. The pawl, however, does not prevent the disks from continuing to rotate after reaching zero position, as the pawl is 30 lifted out of the groove.

In order to prevent the operation of the handle when the re-setting handle is in other than home position, I mount a notched disk 35 62 on the opposite end of shaft 26, (see Fig. 8) which notched disk, when the shaft is rotated, engages the upper end of a swinging plate 63 pivoted at 64 and carrying a bar 65 which lies under the carrying pawls 52, so that when said plate 63 is rocked, the 40 carrying pawls are held out of engagement with the wheel. A rock arm 66 lies against the upper end of plate 63 and when said plate is rocked forwardly, the rock arm 66 is carried with it and being mounted upon 45 a shaft 67, will rock said shaft against the tension of its restoring torsional spring 68. The shaft 67 carries hooked arms 69 which are designed to move under pins 70 on each side member of the rocker frame 16. In 50 this manner, when the plate 63 is rocked, the rocker frame cannot be depressed and hence the operating handle is locked against movement.

To arrest the shaft 26 in zero position, I 55 mount a bell crank lever 71 on the frame 27 which bell crank lever has a stepped upper end for coöperating with a pin 72 on the disk 62 when said bell crank lever is rocked forwardly. The horizontal member of the 60 bell crank lever extends under the plate 63 and when said plate is rocked, the stepped upper end of lever 71 is placed in the path of the pin 72. A spring 73 holds the horizontal member of the bell crank lever 65 against plate 63 so that when said plate

is restored to normal position by dropping into the notch in the disk 62, it will engage the rear edge of said notch and as the restraining pawls 48 tend to center the ratchet wheels, said ratchet wheels will be reversely 70 rotated by the centering restraining pawls practically the distance of one-half a tooth, which reverse rotation releases the stepped upper end of the arresting bell crank lever 71. By this construction, the rocking plate 75 63 places the arresting bell crank lever in position in the path of said pin to arrest said pin when the shaft 26 has been rotated one-half a tooth in excess of one complete revolution. Then, when the plate 63 is released, it will permit the lever 71 to be returned home, and a one-half tooth backward rotation of disk 62 will release the upper end of the arresting lever 71 and permit said 80 arresting lever to move under and behind the pin 72, as shown in Fig. 8.

The drawer releasing mechanism is best shown in Fig. 7 in which 74 indicates a hooked extension on the rocker frame 16 which is adapted to coöperate with a pivoted tappet 75 mounted on a lever 76 pivoted at 77. The rear end of this lever is provided with lateral extensions for engaging a second lever 78 pivoted at 79, the rear end of which is provided with a shoulder which lies in front of the rear wall of the drawer when the drawer is closed. As the operating handle is depressed, the hooked extension 74 engages under the tappet 75 and as the handle rises, the tappet 100 75 is raised and the drawer is released. To sound an alarm when the drawer is opened, I provide the rocking frame 29 with a hooked extension 80, see Fig. 8, which, as the frame 29 is rocked rearwardly, draws 105 back the flat spring 81 carrying the bell hammer the arc of movement of said hooked extension 80, releasing said spring whereby the hammer strikes the bell 82 and sounds the alarm. On the forward rocking movement of the frame 29, the hooked extension 80 again becomes engaged with the upper 110 end of the flat springs 81.

To operate the indicating cylinders: I shall first describe the manner of operating 115 the "Cash" and "No sale" cylinder provided with these words, which are exposed through suitable sight openings at the front and rear of the machine. This cylinder is indicated at 83, see Figs. 2, 3 and 4, being 120 loosely mounted upon a shaft 84 and carrying a ratchet wheel 83^a conjoined thereto. This ratchet wheel coöperates with a restraining pawl 85 pivotally mounted on a rod 86 and connected to a suitable spring 125 whereby it is yieldingly held against the ratchet wheel.

Referring now to Fig. 20, it will be observed that the lever 44^a is provided with a pin or roller operating in a slot in the lower 130

end of a rod 87. This rod is connected to the cylinder 83 and when the operating lever is depressed to open the drawer without registering an amount in the totalizers the 5 rod 87 is raised and rotates the cylinder 83, so as to exhibit "No sale" through the sight openings. The restraining pawl 85 holds the cylinder 83 in this position.

When the operating handle is moved to 10 register an amount in the totalizers, the tap-pet 17^a on the rear end of the extension 16^a of the rocking frame, vibrates the lever 18, causing the upper end thereof, having a slot and pin connection with a rock arm 88, 15 to rock shaft 89 which shaft carries an arm 90 having a bent upper end which, when the arm 90 is rocked forwardly, engages the restraining pawl 85 and releases the ratchet of cylinder 83. The weight of the arm 87 connected to one side of the cylinder 83 rotates said cylinder, so that the word "Cash" 20 appears opposite the sight openings, the movement of the cylinder in reaching this position being determined by the slot in the lower end of the arm 87 and when the arm 90 rocks rearwardly the restraining pawl 85 is again permitted to engage its ratchet.

The dollars indicating cylinder is shown in Fig. 18 at 91 and is conjoined to a bail-like extension 92 whose opposite end is 30 loosely mounted on the shaft 84 and conjoined to a pinion 93. A torsional spring 94 arranged on shaft 84 tends to restore the cylinder 91 to zero position. The segment 95 meshes with the pinion, said segment being loosely mounted on a shaft 86. The lower extension of the segment is provided with a lateral projection 97 which co-operates with a ratchet toothed segment 98. 35 This segment 98 is operated by a pawl 99 mounted on the lower end of a pawl carrying arm 100 swinging from the shaft 86. This pawl carrying arm is connected by a link 101 with the segment 98, so that at each 40 operation of the operating handle to register \$1.00 in the totalizer wheels, the dollar cylinder will be moved to indicate 1. The spring 102 normally holds the pawl 99 in operative position. To release the dollar cylinder, I fix to the rock shaft 89, a curved arm 103 whose forward end lies over a pin 104 on the pawl 99, so that when the extension 16^a of the rocking frame is raised and rocks the shaft 89 in the manner heretofore 45 described, the arm 103 will be depressed, so as to release the pawl 99 and permit the segment 98 to be restored to normal position. A restraining pawl 105 is pivoted to the lower rear portion of arm 103 and co-operates with teeth on the ratchet segment 98 to hold the same in adjusted positions during the successive registrations of several numbers constituting the total amount 50 of the sale, as, for instance, if the sale 55 amounted to \$1.89, a "composition" key is

depressed, so that when \$1.00 was registered in the totalizer, then \$.85 and finally \$.04, the several indicating cylinders would remain so as to exhibit the composition number resulting from the several operations of the handle. The pawl 99 normally lies in advance of the ratchet teeth on the lower edge of segment 98 and the arm 100 which determines the normal position of the segment 98 co-operates with a lateral projection 98^a on the forward edge of the segment, so that as the arm 100 rocks forward, the segment will be moved by the arm 100 and place said segment in position, so that the pawl 99 will engage the first tooth. 75 After this in successive operations to introduce dollars into the machine, the pawl 99 will successively advance the segment 98 up to three additional teeth and the restraining pawl 105 will hold the segment in 80 such advanced position, unless, of course, the shaft 89 rocks.

By means of the restraining pawls 105 the amount indicated on the indicating cylinders will remain exposed until another 90 amount is registered by depressing the handle when pawls 105 are disengaged from their ratchets on the initial downward stroke of the handle through the means which rotates shaft 89.

106 indicates the units cents indicating cylinders, which are fixed to a shaft 84, so as to rotate therewith. Shaft 84 also has a pinion 107 pinned thereto with which co-operates a segment 108 connected by a link 100 109 co-operating with ratchet toothed segments 110 operated by a pawl on an arm 111 in the manner heretofore described with respect to the operation of the segment 98.

The tens or dimes indicating cylinders 105 112 are mounted on shaft 84 and arranged on each side of the dollars indicating cylinder 91. These cylinders have pinions 113 conjoined thereto with which co-operate segments 114 fixed to the shaft 86. Shaft 86 110 also has a ratchet toothed segment 115 operated directly by an arm 116 co-operating with a lateral projection 117 on the forward edge of the segmental ratchet 115, said arm being connected by a link 118 to the segment 23.

By the above construction, whenever units cents are registered, they are indicated by the cylinders 106, the one at the right, looking from the front at the machine being 120 exposed to the front, and the one at the left being exposed to the rear. The dimes indicating cylinders 112 are operated, the one at the right showing through the front, and the one at the left showing through the rear. The dollars indicating cylinder has two series of numbers on it and is exposed at both front and rear.

To indicate a number composed of several smaller numbers resulting from suc- 130

cessive operations of the operating handle, which requires that the indicating cylinders be held in their adjusted position without being released, I depress a key or lever 119 arranged at the front of the machine, see Figs. 1 and 4 which key is provided with a notch 119^a for coöperating with a plate whereby it may be held depressed. A spring 120 arranged under the key tends to raise the same. A bell crank lever 121 pivoted at 122 in the side framing of the machine has its lower member connected to a link 123. The rear end of said link being slidingly mounted upon a bar 124 also pivoted at 122. This link 123 carries a lateral projection 125 at its rear end which, when the key 119 is depressed, is placed over the extension 16^a of the rocker frame, so that when said rocker frame is vibrated by the operating handle, the bar 124 will be raised. When the bar 124 is raised upon the operation of the handle, a downward extending track portion 126 at the rear end thereof is moved into position so that it forms a continuation of the rear edge of lever 18 and holds the pawl 17^a elevated when the extension 16^a is depressed, to prevent the roller on the forward end of said tappet or pawl 17 from dropping under the inclined lower edge of lever 18. Thus after setting the composition key 119, the tappet 17^a will, upon the first operation of the handle, vibrate lever 18 and rock the shaft 89, so as to release all of the indicating cylinders. The bar 124 being raised will locate the track extension in position to prevent the tappet 17^a from again vibrating lever 18 during the successive operations of the handle. By virtue of the restraining pawls operating with the segments 98, etc., the cylinders will be left in their adjusted position. To illustrate: If \$1.59 is to be indicated it makes no difference which amount, \$1.00, \$.55 or \$.04 is registered or indicated first, but assuming for purposes of illustration that \$1.00 is first indicated, the operation of the handle will first release all of the positioned cylinders and position the dollar cylinder to indicate 1. By moving the operating handle to 55 and depressing it, the dimes and cents cylinders will be operated, but the dollar cylinder will not be released. Thus \$1.55 will be indicated. By adjusting the handle to register \$.04 and depressing it, 4 will be added to the cents cylinders, and they will stand at 9, the other cylinders remaining in their position, so that the amount \$1.59 a number composed of three smaller numbers will be indicated on the cylinders. In order to hold the bar 124 elevated after the first operation of the handle in indicating a composition number, I utilize the following means: The forward end of bar 124 carries a bell crank lever 127 whose vertical member is stepped at its up-

per end so as to coöperate with a pin 128 extending from the side frame 2. A spring 129 holds the bell crank lever against the pin and when the rear end of bar 124 is raised, this bell crank lever is depressed, so that its stepped upper end is located under the pin 128 to hold the forward end of the bar 124 depressed and its rear end elevated. To release the bar 124 when the composition number has been indicated, I provide an extension 121^a on the bell crank lever 121 which lies under the horizontal member of the bell crank lever 127 and when the key 119 is released and permitted to rise, this extension 121^a moves the bell crank lever 127 to disengage its stepped upper end from the pin 128 and the bar 124 may return to normal position.

In order to prevent abnormal operation of the indicators when the composition key is depressed and the operating handle operated improperly, I provide means whereby the dollars indicating cylinder cannot be operated to indicate a number higher than 4, \$4.99 being the capacity of the present machine.

As shown in Fig. 19, it will be seen that the ratchet toothed segment 98 has certain of its teeth cut away, so as to leave a blank space 98^b. It will be understood that the purpose of the composition key is to indicate the amount of the sale to the purchaser and no single indication can be higher than \$4.99. If it is desired to indicate \$4.99, the handle is operated four times opposite the dollar scale mark with the composition key depressed, then the handle is operated once to indicate \$.95 and placed opposite the \$.04 and depressed to add 4 to the cents indicators. At no time are the dimes indicating wheels intended to be operated more than once in the indication of a composition number, but as seen above, the dollars indicating wheel may be operated initially to indicate \$1.00 and supplementally to indicate \$2.00, \$3.00 or \$4.00. The cents ratchet toothed segment 110 may be initially operated to indicate 1, 2, 3, or 5 by the arm 111 and supplementally operated to indicate 1, 2, 3, 4, 6, 7, 8, and 9. The space 98^b on the segment 98 prevents the operating pawl 104 from moving the dollars indicator to indicate a number higher than 4, 4 being the limit of movement of this indicating wheel. I provide other means on the cents segment 110 (see Fig. 19^a) in the form of a track plate 110^a on the lower rear edge of the segment which, when the segment is advanced to indicate 9, will engage the pin 110^b on the driving pawl 110^c and depress said pawl, so that it will be moved out of engagement with the teeth on said segment. The restraining pawl 110^d prevents backward rotation of the segment until the rock arm 89 is operated. In this manner the segment 110 may be initially 130

positioned by its arm 111 to indicate 5, and then supplementally positioned by the pawl 110° to indicate 6, 7, 8 or 9. When in the ninth position, the pawl is disengaged and any subsequent operation of the operating handle to register cents, will idly vibrate the pawl 110° which is held out of engagement with the teeth of segment 110 and hence the cents indicating wheel will remain stationary.

To hold the drawer closed during the indication of a composition number and to insure the restoration of the parts to normal position and which were brought into operation to effect such composition indication, I arrange a tappet 130 on the lower end of the bell crank lever 121 which tappet when the key 119 is depressed is moved in front of a shoulder 131 on the drawer. Notwithstanding the fact that the drawer is released by the lever 78 upon the first operation of the handle, and permitted to move forward slightly so that the rear end of the lever 78 will rest upon the top of the drawer, the shoulder 131 engages the tappet 130 and prevents the drawer from being opened until the key 119 is raised. The purpose of making the engagement between the bell crank lever 121 and the drawer in the form of a yielding tappet is to permit the key 119 to be depressed to indicate a composition number when the drawer is open. Then, if the drawer is closed while the key 119 is depressed, the tappet will ride on the edge of the drawer until it drops in front of the shoulder 131 and hence the drawer cannot be again opened until the key 119 is raised.

I will now describe the printing mechanism whereby each number registered is recorded.

The swinging plate 8 before referred to has a plate 132 secured to its lower edge, one edge of which is provided with a series of notches coöoperating with a spring-pressed centering pawl 133, whereby the operating handle is held in registration with its guiding slot. The opposite edge is provided with gear teeth which mesh with a pinion 134 mounted on shaft 135 extending through the side frame 2. This shaft 135 carries a printing wheel 136 on its end, the face of which is provided with printing type representing the different numbers on the scale plate 5. Thus, as the handle is adjusted to different positions, the printing wheel is correspondingly adjusted. As the handle is depressed, a rocking frame 137 (see Fig. 6) is operated, said frame having at one end a lateral extension 138 which lies under an arm 139. The lower end of this arm carries an inking roller 140 which wipes over the face of the type in the printing line as the handle is depressed and moves the inking roller out of the way of the platen or type hammer 142. This type ham-

mer is carried by a rocking frame 143 having a pin at one side which coöperates with a cam slot in the lower end of the plate 144 fixed to the rocking frame 137. Thus, if said frame is rocked, the lower end is moved rearwardly, and as the inking roller is moved rearwardly the platen is lifted so as to press the strip of paper against the type in the printing line. The strip of paper is fed from a spool 145 over appropriated idle rollers on each side of the printing wheel and is wound upon a spool 146. The spool 146 is rotated step by step by paper feeding mechanism which consists of a pawl 147 see Fig. 6, mounted on the rocker frame and coöperating with a ratchet 148 on a shaft 149. This shaft carries a gear 150 on its outer end which meshes with a gear 151 on the hub of spool 146. Shaft 149 also carries one of the paper guiding rollers 149^a which is preferably knurled or faced with rubber. Roller 152 coöperates with the roller 149^a, said roller being mounted in a swinging frame 153 and held yieldingly by a spring 154 against the roller 149^a, so that when said frame is depressed the rollers 159^a and 152 are separated to permit the introduction of the end of the strip of paper.

In order to distinguish the composition numbers which are recorded, I provide means for feeding the paper a shorter distance so that any two or three numbers entering into the composition will be closely spaced. Ordinarily the pawl 147 will operate the ratchet wheel 148 the distance of two teeth but when the composition key 119 is depressed, an extension 123^a on the link 123 will, by a slot and pin connection, rock a plate 155 and move the same in the path of a cam face 147^a on the pawl 147, so that as the rocker frame 16 is depressed, the pawl 147 will be thrown out of engagement with the ratchet when its cam face strikes the plate 155, and on the rising movement of the rocker frame, this cam face permits the pawl to reengage the ratchet at such time as to permit the ratchet to be operated one tooth. The restraining pawl 156 is mounted on an extension of the plate 155 to prevent retrograde movement of the ratchet 148, and also serve to feed the paper one tooth when the composition key is released plate 155 is rotated.

In Figs. 28 and 29, I have shown an arrangement for designating the salesman who operates the machine. There are a series of keys 160 lettered A, B, C, and D, each of which is held up by a spring 161. The shanks of these keys are notched to co-operate with a pawl 162, whereby they are held depressed. The lower ends of the key shanks are connected to T-shaped levers 163 having depending operating extensions of different length so that when a key is depressed it will move a bar 164, by engag-

125

130

ing the bent forward end thereof, different distances. Bar 164 is connected to a printing segment 165 mounted alongside the printing wheel 136, and this printing segment will, when a clerk's key is depressed, position a type in printing line opposite the number recorded, to designate the clerk effecting the registration. The upper extensions of the T-levers 163 coöperate with a plate 166 pivoted at 166^a and connected by a link 167 to a stepped lever 168 pivoted on a rocking plate 169 mounted on shaft 96. When the plate 166 is rocked forward, the stepped lever 168 is brought over a plate 170 mounted on the extension 16^a of the rocking frame, and when the handle is operated, plate 170 engages the particular step in its path and lifts lever 168 rocking the plate 169 so that a retaining pawl 171 may engage the teeth on the lower edge of the plate 169 and hold the same in position. This retaining pawl is mounted upon the rock shaft 89 and when shaft 89 is rocked, it will release the plate 169 and permit the parts to return to zero. Plate 169 operates a segment 172 meshing with the pinion 173 conjoined to the clerk's designating cylinder 174 which cylinder is exposed through the sightopenings and bears letters A, B, C and D. When the rocking frame 16 is depressed, it will pass a tappet 175 in its path and idly vibrate said tappet. This tappet is arranged on an arm 176 fixed to a rock shaft 177 on which the pawls 162 are loosely mounted and said shaft 177 has pins 178 which engage the lateral projections of the pawls, and as the rocking frame 16 rises, it will engage the tappet 175 and rock the shaft to release the keys.

In Fig. 27, I have shown a modified construction of operating handle in which I provide means for securing a pause at the forward rocking movement of the segment 21, 23 and 25 of such duration as to enable the register pinions to be disengaged therefrom while said segments are at rest. In the construction heretofore described in which the rear end of the operating handle rocks said segments forwardly and also operates the rocking frame, the parts so timed that the register pinions must be disengaged from the segments the instant that the handle starts its backward movement and where there is most motion or wear in the parts, this will possibly produce a binding action between the pinions which are held against backward rotation and their operating segments which are starting to move back.

In the modified construction, I pivot bell crank lever 175^a on the plate 8 and provide the rear end of the operating handle with a roller 176^a which coöperates with a cam face in the upper end of the bell crank lever.

The rear end of the bell crank lever is pro-

vided with a lifting plate 177^a pivotally connected thereto and which lifting plate co-operates with the cents, dimes and dollars controlling plates heretofore described. When the handle is operated, the bell crank lever is caused to rock and initially lift one or more of the controlling plates in its path and eventually the rear end of the operating handle will come in contact with the lower edges of said plates to drive them home and take up any lost motion in the pause mechanism under consideration. As the rear end of the operating handle starts downward the roller 176^a will sustain the plate 177^a in its elevated position for a short period of time and hold the register operating segments forward and stationary until the register pinions are rocked out of engagement therewith.

In order to arrest the upward movement of the lifting plates, the horizontal swinging plate 8 is provided with a forward extension 8^a against which all of the lifting plates strike when operated by a handle. To restore the lifting plates, the rocking frame 16 is provided with a T-shaped extension 16^b lying above the arms of the lifting plates, so that if said lifting plate should strike and not fall by gravity, the arms 16^b will depress them.

What I claim is:

1. In a cash register, the combination of a horizontal swinging plate, a vertically movable operating handle pivoted thereto and independently operable lifting plates coöperating with said operating handle.
2. In a cash register, the combination of a horizontally swinging and vertically movable operating handle, relatively positioned vertically movable stepped lifting plates co-operating therewith, segments which are moved by said plates and register wheels which are operated by said segments.
3. In a cash register, the combination of a horizontally swinging and vertically movable operating handle, pivotally mounted stepped lifting plates coöperating therewith, segments connected to said lifting plates, register wheels, and means for moving said register wheels into and out of mesh with said segments.
4. In a cash register, the combination of a horizontally swinging and vertically movable operating handle, stepped lifting plates pivotally mounted so as to move independently of each other, a segment operated by each of said lifting plates, register wheels, and means for moving said register wheels into and out of engagement with said segments.
5. In a cash register, the combination of a vertically movable operating handle, a horizontally swinging plate to which said handle is pivoted, a vertically movable rocker frame which is operated by said

- handle in all of its positions, a registering mechanism, and means for operating said registering mechanism from said rocker frame.
5. In a cash register, the combination of an operating handle pivoted for horizontal swinging movement whereby it may be differentially positioned relative to amount determining devices, and pivoted for vertical swinging movement whereby it is adapted to operate registering mechanism, with a locking means adapted to prevent abnormally sudden oscillation of the handle in a vertical direction, which locking means is adapted to coöperate with said handle in any of its different horizontal positions.
7. In a cash register, the combination of a horizontally swinging plate, an operating handle pivoted to said plate and having a vertical movement relative thereto, and a pivoted member having a cam face engaged by said handle to lock the same against movement when an effort is made to move said handle too quickly.
25. 8. In a cash register, the combination of a horizontally swinging and vertically movable operating handle, a rocker frame operated thereby, register wheels, a swinging frame in which said register wheels are mounted, and means operated by said rocker frame for swinging said frame in which the register wheels are mounted.
9. In a cash register, the combination of a handle, a horizontally swinging and vertically movable operating rocker frame operated by said handle, a swinging frame containing register wheels, a bell crank lever for rocking said swinging frame, a tappet on said bell crank lever, and a notched frame connected to said rocking frame for coöoperating with said tappet and said bell crank lever to rock the register frame.
45. 10. In a cash register, the combination of a horizontally swinging and vertically movable operating handle, a rocking frame operated thereby, a notched segment operated by said rocking frame, a bell crank lever having a tappet which normally lies in position to enter the notch of said rocking frame.
50. 11. In a cash register, the combination of a horizontally swinging and vertically movable operating handle, of pivotally mounted stepped lifting plates which are operated individually and simultaneously by said handle.
12. In a cash register, the combination of a horizontally swinging and vertically movable operating handle, lifting plates which are designed to coöperate individually and collectively with said handle.
60. 13. In a cash register, the combination of a stepped lifting plate having shoulders for registering units of cents, said plate also having spaced projections for registering five cents, and a horizontally swinging
- and vertically movable operating handle co-operating therewith.
14. In a cash register, the combination of a cents lifting plate having spaced projections, a stepped dimes plate in combination with a horizontally swinging and vertically movable operating handle which is designed to be positioned under the projections of the cents plate and between said projections, said handle when operated under the projections of the cents plate operating on two plates conjoined, and when located between the projections of the cents plate operate the dimes plate only.
70. 15. In a cash register, the combination of a horizontally swinging and vertically movable operating handle, stepped dimes and cents lifting plates, having a stepped portion concentric with the movement of said handle, said plates being pivoted at their ends so as to swing vertically and serve as translating devices, actuating racks operated by said plates respectively, and registering mechanism which is thrown into operative engagement with said racks to indicate amounts registered by the machine.
75. 16. In a cash register, the combination of an operating handle, vertically swinging lifting plates operated thereby, a weighted rocking frame coöoperating with said handle to restore the same, said rocking frame also engaging the lifting plates to restore them to normal position.
80. 17. In a cash register, the combination of an operating handle, vertically swinging lifting plates operated thereby, a weighted rocking frame coöoperating with said handle to restore the same, a cylinder positioned by the movement of said rocking frame, said rocking frame also engaging the lifting plates to restore them to normal position, and means for holding said cylinder in adjusted positions.
85. 18. In a cash register, the combination of an operating handle, lifting plates operated thereby, a weighted rocking frame coöoperating with said handle to restore the same, a cylinder actuated by movement of said rocking frame, said rocking frame also engaging the lifting plates to restore them to normal position, means for holding said cylinder in adjusted positions, and means operated by said rocking frame for releasing the cylinder.
90. 19. In a cash register, the combination of a register wheel, of an actuator therefor, an indicator, and means for operating said indicator, said means comprising a segment and a rocking arm for operating said segment, said arm carrying a pawl to engage and operate the segment after the initial operation thereof by said arm.
95. 20. In a cash register, the combination of an indicator, a pinion connected thereto, a segmental rack meshing with said pinion,

- a ratchet toothed segment connected to the segmental rack, an arm for initially operating said ratchet toothed segment, and a pawl carried by said arm for supplementally transmitting motion to said segment. 5
21. In a cash register, the combination of an indicator, and means for operating the same comprising a ratchet toothed segment, an arm for initially operating said segment, 10 a retaining pawl for holding said segment in adjusted position, and a pawl on said arm for supplementally operating said segment and adjusting it to a new position. 15
22. In a cash register, the combination of an indicator, means for operating the same comprising a ratchet toothed segment, an arm for initially operating said segment, a retaining pawl for holding said segment in adjusted position, a pawl on said arm for 20 supplementally operating said segment and adjusting it to a new position, and means for simultaneously disengaging the retaining and supplemental pawls to release the indicator. 25
23. In a cash register, the combination of an indicator, means for operating the same comprising a ratchet toothed segment, an arm for initially operating said segment, a retaining pawl for holding said segment in 30 adjusted position, a pawl on said arm for supplementally operating said segment and adjusting it to a new position, means for simultaneously disengaging the retaining and supplemental pawls to release the indicator, and means for restoring said released 35 indicator to its normal or zero position. 40
24. In a cash register, the combination of a plurality of independently operable indicators, means normally operating to return said indicators to zero, means for releasing all of said indicators to permit them to return to zero after each actuation thereof, and means for preventing the operation of said releasing means, whereby said indicators 45 may be supplementally operated. 50
25. In a cash register, the combination of a plurality of independently operable indicators, means normally operating to return said indicators to zero after each operation, means for releasing all of said indicators to permit them to return to zero, means for initially and supplementally positioning said indicators to indicate a composition number, and means for preventing the operation of said releasing means when a composition number is to be indicated. 55
26. In a cash register, the combination of a plurality of indicators exposed through a sight opening, means for independently operating said indicators to expose different numbers through said opening, means normally operating to return said indicators to normal position after each operation, and means preventing the operation of said releasing means, whereby the numbers exposed 60
- through said sight opening may be changed progressively. 65
27. In a cash register, the combination of a plurality of indicators exposed through a sight opening, means for independently, 70 initially and supplementally operating said indicators to expose different numbers through the sight opening, means normally operating to return said indicators to zero after each operation, and means for preventing the operation of said releasing means when said indicators are supplementally operated. 75
28. In a cash register, the combination of a series of indicators, of retaining pawls for holding them in adjusted position, and means for releasing said retaining pawls comprising a vibrating arm, a tappet on said arm, and a lever rocked by said tappet and means for holding said tappet. 80
29. In a cash register, the combination of a series of indicators, pawls for holding them in adjusted position, means normally operating after each operation for operating said pawls to release said indicators, and means for preventing the release of said pawls whereby the indicators may be supplementally operated. 85
30. In a cash register, the combination of a series of independently operated indicators, normally operating to indicate amounts of single registrations and a composition key and connections whereby said indicators may be progressively operated to display numbers composed of consecutively registered 90 smaller numbers coincident with the successive registrations, a recording mechanism and means for indicating on the record a composition number. 95
31. In a cash register, the combination of a plurality of indicators normally operating to indicate amounts of single registrations, of means for operating them independently, a recording mechanism, a composition key and connection operated by said composition key 100 whereby when said indicators are successively operated to display a composition number, the record will automatically space the numbers entering into the composition numbers differently from the spacing of 105 complete items for the purpose of distinguishing them. 110
32. In a cash register, the combination of a composition key, a drawer, a drawer releasing mechanism normally operating with each operation of the register and means for preventing the operation of said drawer releasing mechanism during operation of the register when said composition key is operated. 115
33. In a cash register, the combination of a series of indicators, of means whereby said indicators may be operated initially and supplementally to indicate a composition number, a drawer, a drawer releasing 120
- 125
- 130

mechanism normally operating coincident with each operation of the indicators, and means for preventing the drawer from opening during the indication of the component numbers of a composition number.

34. In a cash register, the combination of a plurality of independently operable indicators, means normally operating to return said indicators to zero after each registration, and a composition key for preventing the operation of said returning means, whereby said indicator may be supplementally operated.

35. In a cash register, the combination of a plurality of independently operable indicators, means normally operating to return said indicators to zero after each operation, means for initially and supplementally positioning said indicators to indicate a composition number, and a composition key for preventing the operation of said returning means when a composition number is to be indicated.

36. In a cash register, the combination of a plurality of indicators exposed through a sight opening, means for independently operating said indicators to expose different members through said opening, means normally operating to release said indicators and return them to normal position after each registration, and a composition key preventing the operation of said releasing means whereby the numbers exposed through said sight opening may be changed.

37. In a cash register, the combination of a plurality of indicators exposed through a sight opening, means for independently initially and supplementally operating said indicators to expose different numbers through the sight opening, means normally operating to release said indicators and return to zero after each registration, and a composition key for preventing the operation of said releasing means when said indicators are supplementally operated.

38. In a cash register, the combination of registering mechanism indicators, a composition key and connections whereby said registering mechanism and indicators may be initially and supplementally operated, a drawer, drawer operating mechanism, and means controlled by said composition key whereby the drawer operating mechanism is prevented from operating until said composition key is released.

39. In a cash register, the combination of actuators, means for releasing said actuators, a composition key, connections whereby said releasing mechanism is prevented from operating, means for holding said composition key depressed, a drawer, and means for preventing the drawer from being opened while said composition key is depressed.

40. In a cash register, the combination of a horizontal swinging plate, a slotted plate, a handle pivotally mounted to said swinging plate and adapted to coöperate with said slotted plate, and a centering pawl coöperating with said swinging plate.

41. In a cash register, the combination of a horizontal swinging plate, a segment connected therewith and provided with notches in its edge, a centering pawl co-operating with said notches, a slotted plate and a handle pivotally mounted to said swinging plate and adapted to coöperate with said slotted plate.

42. In a cash register, the combination of a comb plate, a vertically movable handle operating in the spaces between the teeth of said comb plate, a horizontal swinging plate to which said handle is pivotally mounted, and means coöperating with said swinging plate for centering the handle over the spaces in the comb plate.

43. In a cash register, the combination of a horizontally movable plate, a handle pivotally mounted to said plate, a rack segment movable with said plate, centering means coöperating with said plate, and a type wheel operated by said plate.

44. In a cash register, the combination of an operating handle, register wheels, actuators therefor, means controlled by said handle for throwing said register wheels and their actuators into and out of mesh, and a pivoted member operated by said handle for causing said actuators to pause during the time that the register wheels are being moved out of mesh therewith.

45. In a cash register, the combination of register wheels and their actuators, an operating handle, means controlled by said handle for moving said wheels and actuators into and out of mesh, and an element operated by said actuating handle and having movement independently thereof for arresting the actuators during the time that the register wheels are being moved out of mesh therewith.

46. In a cash register, the combination of an indicator, a register, and an operating handle for said register, means including said handle for initially and supplementally operating said indicator, and including a device for throwing said means out of co-operation with the indicator when the indicator has been moved to the limit of its movement.

47. In a cash register, the combination of an indicator and a toothed member operating in connection therewith, means for initially moving said toothed member and its connected indicator, a pawl for supplementally moving said toothed member, and means which renders said pawl ineffective with respect to said toothed member in sub-

sequent operations when said indicator is moved to certain position.

48. In a cash register in combination, an indicator, an operating handle, means for positioning said indicator from said handle, said means including a rocking plate movable in one direction by said handle, a key, and means operated by said key adapted to retain said rocking plate in adjusted position upon its being moved by said handle.

49. In a cash register, the combination of a register, actuators for introducing numbers into said register, an indicator, means operated from said actuators for positioning said indicator, an operating handle for operating said actuators, means operated by said handle for releasing said indicators to permit their return to zero, and a key controlled means for rendering said last mentioned means ineffective during a plurality of successive operations of the handle.

50. In a cash register, the combination of an accumulating register, a cash drawer, an operating handle, means operated by said handle adapted to release said drawer coincident with the insertion of an amount into said register, a positioning key, and means attached thereby adapted to prevent the operation of said drawer releasing means during the insertion of a plurality of amounts into said register.

51. In a cash register, the combination of an amount register, a cash drawer, an operating handle, means operated by said handle for introducing amounts into said register and simultaneously releasing said drawer, and a key operated means for preventing the release of said drawer during the insertion of a predetermined number of amounts into said register.

52. In a cash register, the combination of an operating handle having pivotal horizontal and vertical movement, a register, a pivotally mounted lifting plate operated by said handle, and means mounted concentrically with said lifting plate and operated thereby for introducing amounts into said register.

53. In a cash register, the combination of an operating handle having pivotal horizontal and vertical movement, a pivotally mounted lifting plate adapted to be oscillated by said handle, an amount register, an indicator, and means pivoted concentrically with said lifting plate and operable thereby adapted to actuate said register and said indicator.

54. In a cash register, the combination of an operating handle having pivotal movement horizontally and vertically, a plurality of concentrically pivoted denominational lifting plates adapted to be oscillated by said handle, a register, an amount indicator, and means concentrically pivoted with each

lifting plate and operable thereby adapted to introduce amounts into said register and to move said indicator to show amounts thus introduced.

55. In a cash register, an operating handle mounted for horizontal and vertical swinging movement, a plate coöperating therewith, a type wheel, printing mechanism operable by the vertical movement of said handle, and means whereby said type wheel is positioned relative to said printing mechanism by the horizontal movement of said handle.

56. In a cash register, the combination of pivotally mounted cents and dimes lifting plates, a similarly pivoted dollars lifting plate located beyond the ends of the operating faces of the other lifting plates, and a handle adapted to oscillate said plates on their pivots.

57. In a cash register, the combination of a universally mounted operating handle, and a plurality of lifting plates extending concentrically to the axis of horizontal movement of said handle.

58. In a cash register, the combination of a universally mounted handle, and a plurality of lifting plates extending concentrically to the axis of horizontal movement of said handle, and register wheels which are operated by the movement of said plates.

59. In a cash register, the combination of a horizontal swinging plate, a vertically movable operating handle pivotally connected to said plate, and adapted to swing horizontally therewith, a plurality of lifting plates extending concentrically to the axis of horizontal movement of said handle, and a stop on the horizontal swinging plate for limiting the movement of the lifting plates.

60. In a cash register, the combination of an operating handle pivoted for universal movement, cents and dimes lifting plates extending concentrically to the axis of horizontal movement of said handle, and a dollars lifting plate arranged beyond the operating faces of said cents and dimes plates.

61. In a cash register, the combination of an operating handle having horizontal and vertical movement, a plate movable horizontal with said operating handle, registering mechanism operated by said handle, and a full stroke mechanism having coöperating elements carried by said handle and said plate.

62. In a cash register, the combination of a horizontally and vertically movable handle, registering mechanism operable thereby, a plate horizontally movable with said handle, and means carried by said plate for preventing overthrow of said register by said operating handle.

63. In a cash register, the combination of a horizontally and vertically movable oper-

ating handle, mechanism operated thereby, a plate movable horizontally with said handle, and a catch mechanism for preventing violent operation of said handle having co-
5 operating elements carried by said plate and said handle.

64. In a cash register, the combination of a frame, a horizontally movable plate pivoted to said frame, an operating handle pivoted on said plate for vertical movement, a printing mechanism having a type carrying member adapted to be positioned by the horizontal movement of said plate, and a registering mechanism including accumulating wheels which are adapted to be positioned by the vertical movement of said handle.

65. In a cash register, the combination of an operating handle, cents, dimes and dollars lifting plates operable thereby, a cash drawer, releasing mechanism therefor operable by said handle, and means operating upon said releasing mechanism to prevent its operation during successive operations of
25 said lifting plates by said operating handle.

66. In a cash register, the combination of

registering mechanism, lifting plates for governing the operation thereof, a movable plate having a stop member adapted to co-operate with said lifting plates, and an operating handle adapted to position said stop member selectively with reference to said lifting plates and to operate said lifting plates.

67. In a cash register, the combination of 35 registering mechanism, lifting plates for governing the operation thereof, a movable plate having a stop member adapted to co-operate with said lifting plates, an operating handle for positioning said stop member 40 with reference to said lifting plates and a guide co-operating with said operating handle for determining the position of said stop member relative to said lifting plates.

In testimony whereof I hereunto affix my 45 signature in the presence of two witnesses, this 30th day of August, 1911.

ELMER E. PATTEN.
